UNITED STATES PATENT OFFICE.

GEORGE PLINY FULLER, OF MINNEAPOLIS, MINNESOTA.

NUT-LOCK.

SPECIFICATION forming part of Letters Patent No. 376,771, dated January 24, 1888.

Application filed September 19, 1887. Serial No. 250,107. (No model.)

To all whom it may concern:

Be it known that I, GEORGE PLINY FULLER, a citizen of the United States, residing at Minneapolis, in the county of Hennepin and State 5 of Minnesota, have invented a new and useful Improvement in Railway-Rail Joints, of which the following is a specification.

My invention relates to an improvement in nut-locks; and it consists in the peculiar construction and combination of devices, that will be more fully set forth hereinafter, and particularly pointed out in the claim.

In the drawings, Figure 1 is a perspective view of a railway-rail joint provided with a 15 nut-lock embodying my improvements. Fig. 2 is a horizontal sectional view of the same, taken on the line xx of Fig. 1, and showing the spring-plate in position before being applied to the nuts. Fig. 3 is a similar view 20 showing the position of the spring-plate after the nuts have been screwed home. Fig. 4 is a detached perspective view of my improved device.

A represents the meeting ends of a pair of 25 railroad-rails.

B represents the usual fish-plates, which are arranged on opposite sides of the shanks of the rails and serve to connect the same, and C represents the bolts, of the usual construction, which pass through aligned openings in the fish-plates and in the shanks of the rails. Four of these bolts are preferably employed 30 for each joint, the bolts which are farthest from the ends of the fish-plates being provided with nuts D'.

E represents my improved nut-locking device, which comprises a semi-elliptic flat spring-plate, of steel, or other suitable material, provided on its upper edge with right-angled 40 slits F and G, thereby forming lips H, which lips have their inner ends bent outwardly or offset, and thereby arranging the said lips in a different plane from the spring-plates and parallel thereto. The said lips extend in the 45 same direction, as shown, and the distance between them is such that their free ends are adapted to bear against the side of the intermediate nuts, D'. The spring-plate E is provided at suitable points with openings I, 50 adapted to receive the shanks of the intermediate bolts, and the length of the said spring-

plate is such that when it is pressed flat against the side of one of the fish-plates its ends will bear against the opposing inner edges of the outer nuts, D, as shown.

The operation of my invention is as follows: When attaching the fish-plates to the meeting ends of the rails, the outer bolts are first passed through the fish-plates and the rails, and the nuts B are screwed home on the threaded ends 60 of the said bolts and caused to clamp the fish-plates firmly against the sides of the rail-shanks. The intermediate bolts are then passed through the remaining openings in the rails and fish-plates, and the spring-plate or 65 nut-locking device E is then placed against the outer sides of one of the fish-plates, while in its bowed or bent normal condition, as shown in Fig. 3, the ends only of the said spring-plate bearing against the fish-plate. The spring-plate is then pressed inward toward the fish-plate a sufficient distance to cause the ends of the intermediate bolts to pass through its openings H, when the nuts D' are then screwed onto 70 the intermediate bolts and caused to bear 75 against the outer side of the spring-plate. As the nuts D' are screwed onto the intermediate bolts, they press the central portion of the spring-plate nearer and nearer to the opposing sides of the fish-plate, and thereby straighten 80 out the said spring-plate and cause its ends to travel toward the inner opposing edges of the nuts D. While the nuts D' are being screwed onto the intermediate bolts, they slip over the tongues or detents H, and when the said nuts 85 are screwed home, so as to cause the spring-plate to bear flatly against the fish-plate, the nuts D' are turned in such a position that their edges will be engaged by the lips H, as shown, thereby firmly locking the said nuts 90 G' and preventing them from working loose. The ends of the spring-plates which bear against the inner edges of the nuts D serve to effectually lock the said nuts.

In order to remove the spring-plate, the lips 95 H must be first pressed inward against the fish-plate by means of a suitable clamp or other device, and caused to disengage the nuts D'. While the lips H are thus pressed in, the spring-plate will be kept in contact with the fish-plate 100 at all points of its length, and the nuts D' may be readily unscrewed from the intermediate bolts.

When this has been done, the intermediate bolts are removed, and the clamping devices are then released from the lips H, when the plate E instantly springs to its original normal shape (shown in Fig. 4) and drops from the rail-joint, thereby releasing the nut D, as will be easily understood.

Having thus described my invention, I claim—

- 10 The combination of the rails, the fish-plates, the outer bolts passed through the rails and fish-plates and having the nuts D, the curved spring-plate E, having the lips H, raised horizontally in one edge and projecting in the same direction, and provided with openings I, for the shanks of the intermediate bolts, and the

nuts D', screwed onto the intermediate bolts, bearing against the outer side of the spring-plate, and thereby forcing the latter flat against the opposing fish-plate and causing its ends to bear against the opposing sides of the nuts D, the said nuts D' being engaged when screwed home by the lips H, substantially as described.

In testimony that I claim the foregoing as my own I have hereto affixed my signature in presence of two witnesses.

GEORGE PLINY FULLER.
